(57) **CLAIM**

We claim the ornamental design for a stove, as shown and described.

DESCRIPTION

FIG. 1 is a perspective view of a stove;

FIG. 2 is a top plan view of the stove;

FIG. 3 is a front elevation view of the stove;

FIG. 4 is a right side elevation view of the stove;

FIG. 5 is a left side elevation view of the stove;

FIG. 6 is a rear elevation view of the stove; and,

FIG. 7 is a bottom plan view of the stove.

The dash-dash broken lines shown in the figures depict portions of the stove that form no part of the claimed design. The dash-dot broken lines shown in FIG. 7 depict boundary lines and the broken lines and the areas within the boundary lines form no part of the claimed design.

1 Claim, 5 Drawing Sheets
